UNITED STATES PATENT OFFICE

165,676

PORTABLE HEAVY-DUTY SCALE

Clyde N. Bates, Rutland, Vt.

Application March 22, 1951, Serial No. 14,580

Term of patent 14 years

(Cl. D52—10)

To all whom it may concern:

Be it known that I, Clyde N. Bates, a citizen of the United States, and a resident of Rutland, county of Rutland, State of Vermont, have invented a new, original, and ornamental Design for a Portable Heavy-Duty Scale, of which the following is a specification, reference being had to the accompanying drawings, forming part hereof and in which:

Fig. 1 is a side elevational view of a portable heavy duty scale showing the scale with the inclines in elevated position and the wheels in lowered position to permit transportation of the scale.

Fig. 2 is a top plan view.

Fig. 3 is an end elevational view from the right of Fig. 1.

Fig. 4 is an end elevational view from the left of Fig. 1.

I claim:

The ornamental design for a portable heavy-duty scale, substantially as shown and described.

CLYDE N. BATES.
